UNITED STATES PATENT OFFICE.

ANDREW J. BROOKINS, OF CHICAGO, ILLINOIS.

SELECTIVE APPLICATION VALVE FOR AUTOMATIC TRAIN-CONTROL APPARATUS.

Application filed September 11, 1922. Serial No. 587,436.

To all whom it may concern:

Be it known that I, ANDREW J. BROOKINS, a citizen of the United States, and a resident of Chicago, in the county of Cook and 5 State of Illinois, have invented certain new and useful Improvements in a Selective Application Valve for Automatic Train-Control Apparatus, of which the following, when taken in connection with the drawings 10 accompanying and forming a part hereof, is a specification.

This invention relates to a valve arranged to form an element in an automatic train control apparatus.

15 Among the objects of the invention is to obtain a device which will automatically shut off air from the air storage tank flowing into the train pipe of the air brake system, when the automatic train control apparatus is actuated; to obtain a device which will selectively give a signal to correspond or register with the operation of the automatic train control apparatus in the giving of a caution signal, a danger signal, or in 20 the application of brakes. Additional objects are to obtain an apparatus of the kind named which is simple in construction, having few parts, easily installed, effective in operation, economically made, and not liable 25 to break or get out of order.

In the drawings referred to Fig. 1 is a side elevation of a portion of a locomotive, showing in side elevation a storage tank, an apparatus embodying this invention and associated pipes, and signals, and in diagram 35 an automatic train control apparatus.

Fig. 2 is a vertical section of an apparatus embodying the invention.

A reference character applied to designate 40 a given part indicates said part throughout the several figures of the drawings wherever the same appears.

A represents a portion of a locomotive. B represents a storage tank mounted on the 45 locomotive, into which tank air is forced by mechanism not illustrated and not forming an element in this invention, the air from said tank designed for use in the air brake system of the train. C represents a selective 50 application valve embodying this invention. D, (Fig. 2), represents an inlet port to apparatus C. E represents a conduit or pipe communicating, at one end, with storage tank B and, at the other end, with port D. F, (Fig. 55 2), represents an outlet port to apparatus C,

and G a conduit or pipe communicating, at one end, with outlet port F and, at the other end, with the engineer's valve (H). I represents the train pipe. J represents a train control apparatus, with which the apparatus embodying this invention is designed to be used. J represents a pipe communicating with train pipe I and with the train control apparatus J. K, (Fig. 2), represents a vertically movable valve member in apparatus C, k represents the seat of valve member K. Valve member K is provided with chamber L, and port l from said chamber. M represents a chamber in the shell or casing of the apparatus C, said chamber positioned between the end of valve member K and said shell or casing, and m represents an aperture forming an outlet from said chamber M. The lower end of valve member K is of greater external circumference than is the upper end thereof, and the cylindrical shell of the apparatus in which the valve member is longitudinally movable is so arranged that when said valve member is seated on seat k, an annular chamber (N) is obtained, which extends around said valve member, and with which annular chamber the inlet port D and the outlet port F are in communication. O represents a gland 70 of the stuffing box designed to prevent leakage of air from annular chamber N, and P represents an air retaining ring on valve member K, which is positioned below the port F when the valve member is seated, and is arranged so that when the valve member is raised from its seat to cut off communication between ports D and F it will be positioned above said port F, to prevent leakage of air from said port D to and through port F, by way of the annular chamber N. Q represents a chamber with which chamber L of valve member K is, at all times, in communication. R represents an additional chamber in the shell or case of apparatus C. r represents a longitudinally 75 movable valve in chamber R. S represents a spring arranged to yieldingly maintain valve r in normal position as illustrated in Fig. 2. T represents an annular chamber around valve r, and t represents a passage 80 way communicating with chamber Q and with annular chamber T. U represents a port in communication with annular chamber T when valve r is in normal position, and u represents a port arranged to be in 85 90 95 100 105 110

communication with annular chamber T when valve r is moved to compress spring S, into substantially the position indicated by broken lines in Fig. 2. t^1 represents an air retaining ring on valve r. V represents an inlet to chamber Q. V^1 represents a conduit or pipe from train control apparatus J to inlet V. and W^1 represents a conduit or pipe from said train control apparatus to inlet W of chamber R. X represents an alarm signal designed to be actuated when train control apparatus J registers "caution," and Y represents a conduit or pipe from port U to said signal. X^1 represents a signal which is designed to be actuated when train control apparatus J registers "danger." Y^1 represents a conduit or pipe from port u (Fig. 1), to signal X^1 .

Z represents a rod which is secured on the valve member r, to be moved longitudinally by the movement of said valve member. Z^1 represents a hinged plate which constitutes a visual signal, which is normally in an inclined plane, and not exposed to view to a person in the cab of the locomotive. Rod Z is attached to plate Z^1 , so that as said rod is moved by valve member r it turns plate Z^1 on its hinge (Z^2), into a substantially vertical plane, at which time it can be observed underneath the shell or case of the apparatus by a person in the cab.

When valve member K is in normal position, resting on seat k, any leakage from the annular chamber N is prevented, from flowing into chamber Q.

The apparatus embodying this invention being installed substantially as illustrated in Fig. 1, and the parts thereof in normal position, as illustrated in Fig. 2, air under pressure may flow from storage tank B through conduit or pipe E, port D, annular chamber N, port F, conduit or pipe G, engineer's valve H, into train pipe I.

Assuming the train control apparatus J to function, to register "caution," air under train pipe pressure will flow through said train control apparatus, through conduit or pipe V^1 , and inlet V, into chamber Q of the apparatus embodying the invention, and into chamber L of valve member K, and will thereby move said valve member from its normal position on seat k, and put aperture l in communication with chamber M, and air under pressure will flow through said aperture into said chamber M, and through aperture m to waste. By the above named movement of valve member K, port F is cut out from communication with annular chamber N. At the same time air, under pressure also flows from chamber Q through aperture t into and through annular chamber T, through port U, conduit or pipe Y to and through signal X, sounding said signal.

Assuming said control apparatus J to be

actuated to register "danger," and air under train pipe pressure to flow through conduits or pipes V^1 and W^1 . Said air will move the valve member K, as last above set forth, for "caution" opening aperture l into chamber M, and closing port F, and at the same time air under pressure will flow through the conduit or pipe W^1 , and inlet W into chamber R and will force valve member r longitudinally to put annular chamber T in communication with port u, cutting out communication between said annular chamber and port U, and air will flow from said chamber Q, through aperture t, annular chamber T, port u, conduit or pipe Y^1 to and through signal X^1 , sounding said signal, it being the danger signal. At the same time the rod Z will be moved longitudinally and turn visual signal Z^1 , to expose it to view underneath the shell or case of the apparatus to a person in the cab of the locomotive.

I claim:

1. A casing provided with a chamber in communication with the air supply of a train, means to direct air under pressure to said chamber, in combination with an additional chamber in said casing, a movably mounted member of two diameters in said first chamber, said part of smaller diameter extending through said first chamber, and a seat in said first chamber arranged to contact with said movable member to cut off communication between said chambers. 90

2. A chamber provided with a plurality of ports, one of said ports in communication with the supply of air under pressure to the air brake system of the train on which said chamber is installed, in combination with a movably mounted member in said chamber, said movable member arranged to control communication between said ports, and a seat in said first chamber arranged to contact with said movable member, all arranged so that the pressure of air in said chamber yieldingly forces said movable member to said seat. 100

3. A chamber having a plurality of ports, one of said ports in continuous communication with the supply of air under pressure to the train pipe of an air brake system, to continuously supply air under pressure to said chamber, in combination with a movably mounted member in said chamber arranged to control communication between said ports, an annular internal flange to the wall of said chamber arranged to form a seat for said movable member and said air under pressure in said chamber arranged to yieldingly force said movable member to said seat, and an additional chamber arranged to have air under pressure discharged thereinto from the train pipe, and said chamber in determined relation to said movable member so that air under pressure 115

therein moves said movable member in a determined direction, to cut off communication between said ports.

4. A chamber having an inlet port in continuous communication with the storage tank of an air brake system, and having an outlet port, a movably mounted valve member in said chamber, said valve member also provided with a chamber and a port to said chamber, and said valve member arranged to control communication between said inlet and outlet ports, a seat for said movable member, means, comprising air under pressure in said first chamber to yieldingly force said valve member to said seat, in combination with an additional chamber in communication with said chamber in said valve member whereby air under pressure in said additional chamber moves said valve member in a determined direction against the continuous pressure of air in said first named chamber, said port to the chamber in said valve member arranged to establish communication between said chamber and the atmosphere when said valve member is moved a determined distance in said determined direction.

5. A casing provided with a chamber, an inlet port and an outlet port to said chamber, and an additional chamber within said casing, in combination with a movably mounted valve member in said first chamber and a chamber within said valve member communicating with said additional chamber, and said chamber in said valve member provided with a port arranged to control communication between said chamber and the atmosphere, and means to establish communication between said additional chamber and the atmosphere through signals, and signals.

6. A chamber having a plurality of ports, one of said ports in communication with the storage tank of an air brake system, a movably mounted valve member in said chamber, also provided with a chamber having an outlet, said valve member arranged to control communication between said ports, an annular flange to the wall of said first chamber arranged to form a seat for said valve member, said movable valve member arranged to co-act with air under pressure in said first chamber to be yieldingly forced to said seat, in combination with an additional chamber, an inlet to said additional chamber, said movable valve member arranged to co-act with air under pressure in said additional chamber to be moved in a determined direction.

7. A casing provided with a chamber having inlet and outlet ports and provided with additional chambers, all said chambers in communication, in combination with a movable valve member in said first chamber arranged to control communication between

said ports, said valve member arranged when in normal position to obtain communication between said ports, an inlet to one of said additional chambers and a plurality of outlets to the other one of said additional chambers, said chambers arranged so that air under pressure in said additional chambers co-acts with said valve member to move the same in a determined direction to cut out communication between said outlet port and said first chamber, signals, and selective mechanism in one of said additional chambers to control the outlet thereof in communication with a corresponding signal.

8. A plurality of chambers provided with a communicating passage way, and each of said chambers provided with an inlet for air under train pipe pressure, a plurality of outlets from one of said chambers, signals and pipes communicating with said outlets and signals, respectively, a movable member in said chamber which is provided with outlets, arranged, when in normal position, to establish communication with said passage way and one of said signals, means to yieldingly hold said movable member in said normal position, said movable member arranged to be actuated by air under train pipe pressure to cut out said normally communicating outlet and to establish communication between said passage way and the remaining outlet.

9. A chamber provided with an inlet, in combination with a movable member in said chamber, means to yieldingly hold said member in normal position, said member arranged to be moved by air under pressure flowing through said inlet, a visual signal movably mounted outside said chamber, and a connection between said signal and said movable member, whereby the position of said signal is controlled by the position of said movable member.

10. A chamber provided with a plurality of inlets and a plurality of outlets, in combination with a movable member in said chamber, means to yieldingly hold said member in normal position, said member arranged to permit air to flow through an annular chamber thereon from one of said inlets to one of said outlets and to be moved by air under pressure flowing into said chamber through the other of said inlets to selectively control the one of said outlets in communication with said annular chamber, a visual signal movably mounted outside said chamber, and a connection between said visual signal and said movable member, whereby the position of said signal is controlled by the position of said movable member.
